UNITED STATES PATENT OFFICE.

JOHN B. DYER, OF PITTSBURGH, PENNSYLVANIA, ASSIGNOR TO WESTINGHOUSE ELECTRIC AND MANUFACTURING COMPANY, A CORPORATION OF PENNSYLVANIA.

REGULATOR FOR VARIABLE-SPEED GENERATORS.

1,326,328.

Specification of Letters Patent. Patented Dec. 30, 1919.

Application filed November 7, 1917. Serial No. 200,663.

To all whom it may concern:

Be it known that I, JOHN B. DYER, a citizen of the United States, and a resident of Pittsburgh, in the county of Allegheny and State of Pennsylvania, have invented a new and useful Improvement in Regulators for Variable-Speed Generators, of which the following is a specification.

My invention relates to an automatic regulator for the field excitation of a variable speed generator such, for instance, as a generator that is mounted upon an automobile or other vehicle and is adapted to supply current to a storage battery and to other devices upon the vehicle.

My invention is an improvement upon the regulator set forth in Hill and Dyer Patent No. 1,180,039, and it has for its object to provide a regulator of the same general character but of more compact and refined construction and better adapted for mounting within the structure of the generator in connection with which it is used.

My invention is illustrated in the accompanying drawing, Figure 1 of which is a view in side elevation of a regulator embodying the same; Fig. 2 is a plan view of the regulator; and Fig. 3 is a simple diagram illustrating its circuit connections.

The regulator comprises an electromagnet having a U-shaped magnetizable member 1 that provides the outer legs of the electromagnet, and a central cylindrical leg or member 2 that is threaded in the member 1 and is provided in its threaded end with a slot for the reception of a screw-driver for effecting adjustment of the operation of the regulator. The threaded end of the central leg 2 is also provided with a lock nut 3 for securing the member in its adjusted position. The other end of the central leg 2 is somewhat enlarged so as to constitute the main pole of the electromagnet. The central leg 2 is surrounded by a main energizing coil 4 that is connected in shunt to the armature of the generator 28 in connection with which the regulator is used. In some cases, it may be preferable or desirable to employ a small series coil 6 also which is adapted to be connected in series with the armature 5, as shown in Fig. 3, and preferably arranged to oppose the coil 4.

Attached to the ends of the U-shaped

magnetizable core member 1 by means of screws 7 and rivets 8 is a brass, or other suitable non-magnetic plate or member 9 that is provided with perforated lugs or ears 10 between which an armature 11 is pivotally mounted, the armature extending across and adjacent to the flattened end of the central core leg 2 which projects through the plate 9. The armature 11 is restrained from engagement with the end of the member 2 by means of two plate springs 13 and 14 that are pivoted thereto at one end, the free end of the spring 13 engaging a stop or lug 15 that constitutes a part of the plate 9. The spring 13 is bi-metallic, that is, it is composed of two different metals, such as nickel and steel, that have different température-expansion co-efficients, for a reason which will be more fully explained hereinafter. The free end of the spring 13 is separated somewhat from the spring 14 in order that it may serve as the main restraining means for the movements of the armature under normal conditions.

Attached to the spring 14 is a contact member 17 that is adapted to engage and disengage a coöperating contact member 18 carried by another plate spring 19, one end of which is rigidly attached to the U-shaped magnetizable core by means of the rivets 8, insulating pieces 21, however, being employed to insulate the bracket from the other parts of the regulator. The bracket 20 is also provided with an ear or lug 22 to permit of connecting the same to the circuit to be controlled by the regulator. Attached to the free end of the spring 19 on the side opposite the contact member 18 is a fiber, or other suitable wear piece, 23 that is adapted to engage a cam or eccentric 24 mounted upon or driven by the shaft of the generator the excitation of which is controlled by the regulator. When the generator speed and voltage attain predetermined values the armature 11 is attracted and the contact member 17 is raised slightly. The cam or eccentric 24 then serves to vibrate the contact member 18 into and out of engagement with the member 17 at a rate proportionate to and dependent upon the speed of the generator. The plate 9 is provided with a lug or ear 25 to which the ends of the coils 4 and 6 are connected. The core member of

the device being connected to ground, the terminals of the coils and the contact member 17 are thus grounded.

The contact member 18 is connected to a suitable point in a resistor 26 a portion of which is included in series with the shunt field magnet winding 27 of the generator 28, and, consequently, the degree of excitation of the said field magnet winding is caused to depend upon the effective value of the resistance of the resistor 26, which is, in turn, controlled by the engagement and disengagement of the contact members 17 and 18. The position of the contact member 17 depends upon the degree of excitation of the electromagnet produced by the coils 4 and 6 which are connected in opposition to each other. Thus, as the voltage of the generator increases, the contact member 17 is caused to recede from the terminal 18 so that the effective value of the resistance in the field circuit will be somewhat increased to effect a reduction in the excitation of the field magnet winding and, therefore, of the voltage of the generator. Likewise, as the current delivered by the generator increases, the current in the coil 6 increases correspondingly. Since the magnetizing effect of this coil is opposed to that of the coil 4, the pull upon the armature is somewhat decreased so as to permit of a reduction in the effective value of the resistance of the resistor 26, and, therefore, of an increase in the excitation of the field magnet winding 27 which increases the voltage to enable the generator to carry the increased load without substantial reduction in its voltage.

As the generator temperature increases, due to its operation under load, the increased temperature is communicated to the bimetallic plate spring 13 and, owing to the different rates of expansion of the two metals which compose it, the restraining force of the spring upon the armature is somewhat decreased in accordance with the increase in the temperature of the generator structure. The effect of the decreased restraining force of the spring is to make it possible for a smaller current in the series coil 6 to cause an increase in the effective value of the resistance in the field circuit so that the generator will tend to carry less load after it has become heated than when cool. The resistances of the regulator coils 5 and 6 will also change with changes in temperature, and the bi-metallic spring 13 also operates to compensate for such changes. Similarly, the operation of the regulator will be effected by atmospheric temperature so that, when the weather is warm the regulator will cause the generator to deliver less current at a given speed than when the weather is cold.

The structure of the electromagnet may also be employed in other devices than regu-

lators, such, for instance, as cut-out devices employed for controlling the connections of a generator to a battery that is adapted to be charged thereby when the voltage of the generator exceeds the voltage of the battery.

I claim as my invention:

1. A regulator for dynamo-electric machines comprising an electromagnet having an energizing winding, an armature therefor that is pivoted at one end, a plate spring attached to the armature and extending beyond its free end, a stop with which the said spring engages, a pair of co-operating contact members one of which is actuated by the armature, another plate spring on one end of which the other contact member is mounted and the other end of which is rigidly supported, and means for actuating the latter spring.

2. A regulator for dynamo-electric machines comprising an electromagnet having an energizing winding, an armature therefor that is pivoted at one end, a bi-metallic plate spring attached to the armature and extending beyond its free end, a stop with which the said spring engages, a pair of co-operating contact members one of which is actuated by the armature, another plate spring on one end of which the other contact member is mounted and the other end of which is rigidly supported, and means for actuating the latter spring.

3. A regulator for dynamo-electric machines comprising an electromagnet having an armature pivoted at one end, a plate spring attached to the armature and extending beyond its free end, a stop with which the said spring engages, a pair of co-operating contact members one of which is actuated by the armature, another plate spring on one end of which the other contact member is mounted and the other end of which is rigidly supported, a wear piece attached to the latter spring, and a cam that engages the said wear piece and is actuated by the dynamo-electric machine.

4. A regulator for a dynamo-electric machine comprising a U-shaped magnetizable member, a central adjustable leg therefor, an energizing winding surrounding the said central leg, an armature pivoted to one of the outer legs of the magnetizable member and extending adjacent to the central leg, a plate spring attached to the armature and extending beyond its free end, a stop with which the said spring engages, a pair of co-operating contact members one of which is actuated by the armature, another plate spring upon one end of which the other contact member is mounted and the other end of which is rigidly supported, and a cam driven by the dynamo-electric machine for actuating the latter spring.

5. A regulator for a dynamo-electric ma-

- chine comprising a U-shaped magnetizable member, an adjustable central leg therefor, an energizing winding surrounding the central leg, an armature that is pivoted to one of the outer legs of the magnetizable member and extends adjacent to the central leg, two superposed plate springs one of which is bi-metallic, attached to the armature and extending beyond its free end, a stop with 5 which the said springs engage, a pair of co-operating contact members one of which is actuated by the armature, another plate spring upon one end of which the other contact member is mounted and the other end 10 of which is rigidly supported, and a cam driven by the dynamo-electric machine for actuating the latter spring.
6. A regulator for a dynamo-electric machine comprising a U-shaped magnetizable member, an adjustable central leg therefor, an energizing winding surrounding the central leg, a non-magnetizable plate attached to the ends of the legs of the magnetizable member, an armature that is pivoted to said 15 plate and extends across the end of the said central leg, a bi-metallic plate spring attached to the armature and extending beyond its free end and engaging a portion of the said non-magnetizable plate, a pair of 20 co-operating contact members one of which is actuated by the armature, another plate spring upon one end of which the other contact member is mounted and the other end 25 of which is rigidly attached to but insulated 30 from the non-magnetizable plate, and a cam driven by the dynamo-electric machine for actuating the latter spring.
7. An electromagnetic device comprising a U-shaped magnetizable member, a central adjustable core leg mounted in the said member, an energizing winding surrounding the said central leg, an armature pivoted to one of the outer legs of the magnetizable member and extending adjacent to the central leg, a plate spring attached to the armature and extending beyond its free end, a stop with 35 which the said spring engages and a pair of co-operating contact members one of which is actuated by the armature.
8. An electromagnetic device comprising a U-shaped magnetizable member, a central longitudinal adjustable core leg mounted in the said member, an energizing winding surrounding the said central leg, a non-magnetizable plate attached to the ends of the legs of the magnetizable member, an armature that is pivoted to the said plate and extends adjacent the end of the said central leg, a plate spring attached to the armature and extending beyond its free end and engaging a portion of the said magnetizable plate, and a pair of co-operating contact members one of which is actuated by the armature.

In testimony whereof, I have hereunto 50 subscribed my name this 30th day of Oct., 55 1917.

JOHN B. DYER.
